SAFETY LOCKING DEVICE FOR HOOKS

Lester W. Manbeck, Lewistown, Pa.

Application July 3, 1934, Serial No. 733,641

4 Claims. (Cl. 24—241)

This invention relates to a safety locking device for hooks, and it is an object of the invention to provide a device of this kind which can be readily and conveniently applied to any standard hook.

Another object of the invention is to provide a device of this kind which when in applied position effectively operates to prevent accidental separation of the hook from its work and also to provide a device of this kind which may be easily applied to the hook or removed therefrom.

The invention consists in the details of construction and in the combination and arrangement of the several parts of my improved safety locking device for hooks whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a view in side elevation of a safety device constructed in accordance with an embodiment of my invention and in applied position, the associated work engaged with the hook being shown in section;

Figure 2 is a sectional view taken substantially on the line 2—2 of Figure 1;

Figure 3 is a view in elevation of one of the members comprised in my improved safety locking device as herein set forth;

Figure 4 is a view in elevation from the inner side of the second member or plate comprised in the device as herein set forth.

As disclosed in the accompanying drawing, H denotes a standard or conventional type of hook with which is adapted to be employed a safety locking device constructed in accordance with an embodiment of my invention. My improved device as herein disclosed comprises two members A and B. The member A comprises in its structure the body portion I which is insertable within the hook H from a side thereof, said member being substantially cylindrical in form and of a major diameter in excess of the space between the outer portion of the bill 2 and the shank 3 of the hook. This body portion I is also of a length in excess of the thickness of the hook. The body portion I is provided in its periphery with a relatively large notch or recess 4 which is adapted to receive the work W with which the hook may

be engaged, said work being herein disclosed as a ring.

One side of the body member I has extending therearound from opposite sides of the notch 4 an outstanding flange 5, said flange increasing in width from opposite sides of the notch 4 to a point substantially diametrically opposed thereto, said flange at opposite sides of the notch 4 being substantially flush with the periphery of the body portion I. The flange 5 provides a stop to limit the extent of insertion of the body portion I laterally through the hook H so that when the second member or plate B is engaged with the opposite end of the body portion I the device is effectively held against accidental displacement or removal with respect to the hook H.

The member or plate B when applied is concentric to the flange 5 and has in a marginal portion thereof a notch or recess 6 for registry with the notch or recess 4 in the body portion I of the member A. The applied member or plate B provides a second flange projecting beyond the periphery of the body portion I for coaction with the adjacent side of the hook H to prevent retraction of the body portion I after being placed through the hook H.

Extending from the inner face of the member B eccentric to the axial center thereof but at substantially the transverse center of the notch 4 is an elongated pin 7 welded or otherwise secured to the member B. This pin 7 is of a length to freely extend through the body portion I and project a distance therebeyond. The body portion I is provided therethrough with an opening 8 eccentric to the axial center of the body portion I but at substantially the transverse center of the notch 4 and through which the pin 7 is inserted.

With the body portion I placed within the hook H and after the pin 7 has been directed through the opening 8 of the member A a retaining ring 9 or the like is inserted through an opening 10 in the extended end portion of the pin 7 to hold said pin 7 against withdrawal from applied or working position. However, when the ring or member 9 is removed the member B may be readily separated from the member A to effect a convenient and quick removal of my improved safety locking device.

The periphery of the body portion I at a desired point intermediate its ends a as determined by the notch or recess 4 is provided thereacross with an outstanding lug 11. This lug 11, when the device is in applied position, has contact with the bill 2 or the shank 3 of the hook whereby the extent of rotation of the applied device is

positively limited so as to prevent the notches or recesses 4 and 6 to register with the space between the outer end portion of the bill 2 and the shank 3 which would permit separation of the work W from the hook H and which separation it is the purpose of my improved device to prevent.

In practice the work W is engaged with the hook H whereupon my improved safety locking device is applied to the hook with the work received within the notches or recesses 4 and 6. My improved device as herein disclosed when applied is allowed to have limited oscillation within the hook and this is of advantage when the hook is employed with heavy work, such as in connection with a crane or the like, as such oscillating movement will allow certain freedom of the work with respect to the hook H to facilitate the desired operations of the crane.

The shank 3 as herein disclosed has disposed through its outer portion adjacent a margin thereof a member 12 having eyes 14 at its extremities. To one of these eyes 14 is attached a chain 15 or kindred flexible member of desired length and which member has its opposite or outer end portion secured to the peripheral portion of the member B, said member B being provided therethrough with a suitably located opening 16 to facilitate such connection.

The second eye 14 has secured thereto an end portion of the elongated chain or flexible member 17 which has its outer end portion connected to the peripheral portion of the flange 5 of the member A, said flange having therethrough an opening 18 to facilitate such connection. Connected to the chain or member 17 intermediate its ends is the extremity of a third chain or flexible member 19 which has its opposite or outer extremity suitably connected, as at 20, to the retaining ring 9. The chains or flexible members 15, 17 and 19 are provided to prevent misplacement or loss of the members A and B and ring 9, it being understood of course that such chains or flexible members are of a length sufficient to offer no hindrance or obstruction to the desired manipulations of the members A and B and the ring 9 in either applying the device to the hook or removing the device therefrom.

From the foregoing description it is thought to be obvious that a safety locking device for hooks constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A safety locking device for hooks comprising a body to be inserted laterally through the hook, means carried by an end portion of the body to limit the extent of insertion of the body through the hook, means detachably engageable with the opposite end portion of the body after it has been inserted through the hook for holding the body against retraction, said body in its periphery having a recess to receive the work engaged over the hook, said body having a diameter in excess of the space between the outer portion of the

bill of the hook and the shank of the hook, and means carried by said body and extending within said space for limiting the turning movement of the body when applied to the hook to prevent the recess of the body coming into register with the space between the outer portion of the bill of the hook and the shank of the hook.

2. A safety locking device for hooks comprising a body to be inserted laterally through the hook, means carried by an end portion of the body to limit the extent of insertion of the body through the hook, means detachably engageable with the opposite end portion of the body after it has been inserted through the hook for holding the body against retraction, said body in its periphery having a recess to receive the work engaged over the hook, said body having a diameter in excess of the space between the outer portion of the bill of the hook and the shank of the hook, and a lug extending out from the periphery of the body into the space between the outer end portion of the bill of the hook and the shank of the hook for contact with the outer end portion of the bill of the hook or with the shank of the hook to limit the turning movement of the applied body to prevent the recess of the body from coming into register with the space between the outer portion of the bill of the hook and the shank of the hook.

3. A safety locking device for hooks comprising a body to be inserted laterally through a hook and having a recess in its periphery to receive the work engaged over the hook, a flange carried by one end of the body for contact with a side of the hook to limit the extent of insertion of the body through the hook, a plate member detachably connected with the body, said plate member overlying the opposite end of the body and extending beyond the periphery thereof for contact with the adjacent side of the applied body to hold the applied body against retraction through the hook, and means carried by the body to extend within the space between the outer portion of the bill of the hook and the shank of the hook for limiting the extent of rotation of the applied body to prevent the notch of the body registering with the space between the outer end portion of the bill of the hook and the shank of the hook.

4. A safety locking device for hooks comprising a substantially cylindrical body to be inserted laterally through the hook, said body in its periphery having a recess to receive the work engaged over the hook, said body having a diameter in excess of the space between the outer portion of the bill of the hook and the shank of the hook, an outstanding flange at one side of the body extending therearound from opposite sides of the recess, said flange at opposite sides of the recess being substantially flush with the periphery of the body and increasing in width from said opposite sides of the recess to a point substantially diametrically opposed to said recess, a plate member detachably overlying the opposite side of the body, and means for holding said plate member in position, said plate extending beyond the periphery of the body for contact with the adjacent side of the hook to hold the body against retraction through the hook, said plate having a recess registering with the recess of the body and being of a diameter to extend beyond the periphery of the body from opposite sides of the recess.

LESTER W. MANBECK.
